UNITED STATES PATENT OFFICE

MALCOLM E. HENNING, OF DES MOINES, IOWA, ASSIGNOR TO PENN ELECTRIC SWITCH CO., OF DES MOINES, IOWA, A CORPORATION OF IOWA

DEFROSTER

Application filed October 27, 1932. Serial No. 639,808.

An object of my invention is to provide a control switch with defrosting mechanism which is simple, durable and comparatively inexpensive to manufacture and assemble in 5 connection therewith.

Another object is to provide in connection with a movable control member movable through a limited space during controlling operations, a means for modifying the 10 operation thereof over any given period of time desired, such means being selectively operable to modifying or non-modifying position, as desired and being controlled by a control device already provided for the 15 movable control member.

A further object of my invention is to provide a control mechanism for refrigerators comprising means for starting and stopping operation of the refrigerator to obtain 20 normal cycles of operation or permit operation of the refrigerator at a predetermined factory setting and to provide means for securing temporary modification of the factory setting of the refrigerator to obtain different normal cycles of operation which is 25 usually done by the operator of the refrigerator or housewife without loosing the factory setting and to provide means for obtaining non-normal cycles of operation of the 30 refrigerator for defrosting purposes, the temporary modification of the cycles of operation as well as the non-normal cycles of operation being manually controlled by a common means whereby the operator or 35 housewife in connection with domestic refrigeration may secure normal operation of the refrigerator at temperatures other than the factory setting and likewise secure operation of the refrigerator in non-normal 40 cycles for defrosting purposes.

Still a further object is to provide a differential adjusting or modifying means for a control switch which is controlled by the same knob which controls the range, manual 45 stopping and starting or resetting after tripping of the switch to "off" position by reason of an overload cutout mechanism, the modifying means including a spring loaded member which is associated with the knob for being controlled thereby.

Still a further object is to provide in connection with a control member moved by a power element opposed by a spring, a modifying means which assists the spring when moved to operative position and adjusting 55 mechanism for the spring being associated with the modifying means to cause it to assist the spring or remain in an inoperative position relative thereto, as desired.

With these and other objects in view, my 60 invention consists in the construction, arrangement and combination of the various parts of my device, whereby the objects contemplated are attained, as hereinafter more fully set forth, pointed out in my claims, and 65 illustrated in the accompanying drawing, in which:

Figure 1 is a plan view of a control switch with defrosting mechanism embodying my invention associated therewith, part of the 70 cover plate being removed from the casing and parts of the mechanism being shown in section to better illustrate the associated parts of the device.

Figure 1A is a partial view of Figure 1 75 showing the parts in a different position.

Figure 2 is a front elevation of the switch structure.

Figure 3 is a sectional view on the line 3—3 of Figure 1; and 80

Figure 4 is a perspective view of the defrosting lever.

On the accompanying drawing, I have used the reference numeral 10 to indicate generally a switch housing. It has a front 85 plate 12 provided with a hub 14 in which a control knob 16 is both rotatable and slidable toward and away from the front plate 12.

With respect to the interior mechanism of the switch structure, an operating arm 18 90 has two ears 18a pivoted on a pin 20. The operating arm 18 is operated by a pressure or temperature bellows 22 opposed by a spring 24. The left end of the spring 24 is seated in a washer 25. The washer 25 has lugs 25a 95 pivoted in forks 18b of the arm 18 (two lugs and two arms being provided for proper balance to prevent binding). The arm 18 carries a pointed member 26 engaging one end of an overcenter spring 28, the opposite end 100

of which engages a pointed member 30 of a switch operating arm 32. The arm 32 has lugs 34 pivoted in depressions 36 of a frame member 38.

5 Adjacent the lower wall of the casing 10 in Figure 1, a slidable contact bar 40 is shown. It carries a contact 42 adapted to engage a stationary contact 44 whereby to establish an electric circuit when the contacts 10 are together. A spring 46 serves to retract the contact 42 from the contact 44 when the arm 32 permits it to do so.

The tension of the spring 24 is adjustable by the knob 16 which is secured to a sleeve 48. 15 The sleeve 48 has internal teeth 50 engaging serrations 52 of an adjusting screw 54. The adjusting screw 54 is screwed through a cap 56 which is non-rotatable relative to the casing 10.

20 From the foregoing description, it will be obvious that the switch arm 32 is automatically controlled, depending upon pressure in the bellows 22.

The switch is primarily designed for controlling a mechanical refrigerator and does so by engaging the contacts 42 and 44 when the temperature rises to a predetermined high degree and separating them when it lowers to a predetermined low degree.

25 30 Within the adjusting screw 54, a differential adjusting screw 54a is provided. It is screw-threaded relative to the range adjusting screw 54 and its left end serves as a stop for an extension 32a of the switch operating arm 32. By removing a screw 16a in the knob 16, access can be had to the differential adjusting screw 54a to change its position and consequently the limit to which the arm 32 can swing in a clockwise direction, thus 35 40 changing the differential of operation of the arm 32.

The serrated tooth connection at 50 and 45 52 permits a factory adjustment by removing the screw 16a with the pointer on the knob 16 at any of the indicating numerals on the face plate 12 corresponding to the number of graduations it is desired to change the adjustment. A screw driver or pin is then inserted through the bore of the sleeve 48 50 and the screws 54 and 54a are pushed inwardly against the tension of the spring 24 until the serrations 52 are free of the teeth 50. The knob 16 is then returned to the "defrost" position and the spring 24 released whereupon 55 60 the serrations 52 will again seat in the teeth 50 and the range will have been changed, as desired. Thereafter the knob 16 will have the same range but the range will be at a lower setting. To raise the setting by this factory adjustment, the knob is rotated from the "defrost" position to the desired graduation, while the adjusting screw 54 is pressed inwardly.

Normally the knob 16 can be rotated 65 through the range of numbers from "1 to 9"

on the face plate 12 in Figure 2 for changing the range of operation. The features just described and a manual "on" and "off" control as well as a manual overload protection reset control are operated by the knob 70 16 and all of these parts are fully disclosed in detail in my copending application Serial No. 635,974, filed October 3, 1932.

The overload protection feature, briefly, involves a ratchet wheel 58 secured to a sleeve 75 60 which in turn is secured by solder to a stationary pin 62. A resistance coil 64 surrounds the tube 60 so that when an overload current flows through the resistance wire, the solder will be melted whereupon the ratchet wheel 58 can rotate.

The ratchet wheel is engaged by a pawl 66 which is operatively connected with a trip arm 68 which is moved toward the right when the ratchet wheel 58 rotates. Upon being 85 moved toward the right, the trip arm 68 engages a lug 70 on the switch bar 40 for separating the contacts 42 and 44.

To reset the overload protection mechanism after it has once tripped out, the knob 16 90 has a plate 72 thereon engaged in a hook 74 of a slidable plate 76. The plate 76 has an extension 76a adapted to engage a second slidable plate 78 and cause it to move the trip arm 68 to a position permitting the spring 46 to close the contacts 42 and 44. 95

It will be noted that the slidable plate 78 has an ear 78a and the trip arm 68 is pivoted to this ear. A spring 80 serves the purpose of constraining the slidable plate 78 toward the right in Figure 1. 100

When the plate 76 is moved toward the left, it also moves the pawl 66 with it for resetting the pawl in a new position on the ratchet wheel 58. Thus the thermal overload cutout is reset by the knob 16. 105

The plate 72 is also operable to move the plate 78 and the trip arm 68 toward the right when the knob 16 is pulled outwardly from its position shown in Figure 1. Thus the knob 16 provides a manual cutout for the switch structure. When the knob 16 is again pushed inwardly, the trip arm 68 moves to the position of Figure 1 whereupon the spring 46 re-engages the contacts 42 and 44. 110 115

Defrosting mechanism

The defrosting mechanism of my present invention comprises a lever A, a spring 82, an 120 adjusting screw 84 for the spring and a cam plate 86 formed on the sleeve 48. The lever A, as shown in Figure 4, has a pair of ears 88. These are pivoted on the pin 20. An extension 90 of the arm A has a cam engaging ear 92 thereon adapted to engage the cam 86.

An abutment 94 is provided on the arm A for one end of the spring 82 to engage. The other end of the spring engages a washer 96 125 130

which is in engagement with the adjusting screw 84.

The screw itself is threaded in the face plate 12 so as to be adjusted relative thereto.

5 The cam 86 has the major portion of its periphery formed on a radius from the center of the sleeve 48. A notch 86a is provided in the periphery and when this is in registry with the extension 90 of the arm A, the defrosting mechanism is in defrosting position, as will hereinafter be more fully described.

As shown in Figure 1, it will be noted that the controlling arm 18 is in its right hand position and that a flange 18a thereof adjacent the pivot 20 is spaced from an edge 90a of the arm A. The arm A is held in this position by the peripheral portion of the cam 86 engaging the ear 92 of the arm A against the tension of the spring 82.

20 When the knob 16 is moved to the defrost position indicated on the face plate in Figure 2, the arm A will drop to the dotted line positions of Figures 1 and 3. In such position, the spring 82 is effective to load the lever 18 against the action of the bellows 22 and thus prolong the cycles of operation of the controlling arm 18 by aiding the tension of the spring 24. As shown in Figure 1A, the lever 18 is in its other extreme position and it will be noted that it is not in engagement with the arm A which is in defrosting position. Thus it is only at one end of the range of movement of the lever 18 that the spring 82 loads it during the defrosting cycles of operation.

The tension of the spring 82 is adjusted by the screw 84 so that the high temperature cut in point of the switch structure can be raised by increasing the tension or lowered by decreasing the tension.

By providing the defrosting adjustment operated by the range changing knob, this one knob acts as a common means to temporarily adjust the operating temperature of the switch structure without losing the factory setting and causes defrosting cycles of operation when set in a predetermined position. The defrosting cycles of operation will continue as long as the knob remains in such position and will be discontinued when it is moved to any of its other positions.

The defrosting position of the knob 16 is preferably at the high temperature end of the limited movement of travel of the knob, 55 since when so arranged, the knob in defrosting position will cause a slight raising of the low temperature end of the differential of operation of the switch structure and a considerable raise in the high temperature end of the differential of operation. This, in order to obtain a defrosting temperature, makes it possible to obtain it with less differential than if the defrosting position were adjacent the low temperature selection end of 60 the travel of the knob.

The knob 16 is used for temperature selection, manual "on" and "off" control and reset control after overload cutout operation has occurred. By my present invention it is also used for controlling the defrosting operation 70 and thus it is obvious that I have provided a single control for any of the mentioned controlling operations in combination with controlling the defrosting operation of the switch structure. 75

Some changes may be made in the construction and arrangement of the parts of my device without departing from the real spirit and purpose of my invention, and it is my intention to cover by my claims, any modified 80 forms of structure or use of mechanical equivalents which may be reasonably included within their scope.

I claim as my invention:

1. A control mechanism for refrigerators 85 comprising means for starting and stopping operation of the refrigerator to obtain normal cycles of operation, means for securing temporary modification of the normal cycles of operation of the refrigerator with the temperature limits between starting and stopping remaining the same, means for obtaining non-normal cycles of operation of the refrigerator with the temperature limits between starting and stopping being changed 90 and common means manually settable for securing either said temporary modification of the normal cycles of operation or said non-normal cycles of operation. 95

2. A control mechanism for the operation 100 of a refrigerator comprising means for starting and stopping the operation of the refrigerator with a fixed differential between starting and stopping, means for changing the range for starting and stopping operation 105 and means associated with and rendered operative or inoperative by said last means for temporarily changing the differential for non-normal cycles of operation of the refrigerator. 110

3. A control mechanism for refrigerators comprising a cyclically operated movable member, means for adjusting the normal range of said member, means in addition to said adjusting means to secure temporary 115 non-normal cycles of operation of the refrigerator and manually controlled means for rendering said last means effective or ineffective, said manually controlled means also serving to adjust said first mentioned means. 120

4. For use with a control mechanism including a cyclically operated movable member and adjustable means for adjusting the normal range thereof, means in addition to said adjustable means for modifying the operation of a device controlled by said control mechanism to secure a temporary non-normal operating cycle comprising a resisting member adapted only upon movement of said adjustable means beyond adjustment of 125 130

the range for normal operation to resist movement of said movable member for securing said non-normal cycle of operation.

5. In combination with an automatically movable member and manually adjustable means movable between predetermined limits to vary the range thereof, mechanism for modifying the cycles of operation of said automatically movable member comprising

10 a resisting member selectively movable to operative and inoperative positions, said manually adjustable means being operatively associated therewith to render it operative to so modify said cycles of operation in one position of the manually adjustable means and to render it inoperative in all other positions of the manually adjustable means.

6. In combination with an automatically movable member operable through cycles of operation and having manually adjustable means movable to travel between predetermined limits to change the range thereof, mechanism for modifying said cycles of operation comprising a modifying member selectively movable to operative and inoperative positions, said manually adjustable means being operatively associated therewith to render it operative to so modify said cycles of operation in one position of the manually adjustable means at one limit of its limited path of travel and to render it inoperative in all other positions thereof.

7. For use with an automatic control device having an alternately oppositely movable member, means to prolong the movement of said movable member in one direction comprising a spring loaded member to be engaged by said movable member and manually operable means to set and retain it in position to be engaged thereby during the latter part only of its movement in such direction to prolong movement of the movable member during such part of its movement or to set and retain it in position spaced therefrom whereby movement of the movable member is not so prolonged.

8. A control mechanism for refrigerators comprising automatic means for starting and stopping operation of the refrigerator to obtain normal cycles of operation with the temperature limits between starting and stopping predetermined, overload protection means for non-normally stopping operation of said refrigerator, means for obtaining non-normal cycles of operation of said refrigerator with the temperature limits between starting and stopping being changed so that the time period before starting is prolonged and common means manually operable for resetting said overload protection means and securing said non-normal cycles of operation.

9. A control mechanism for refrigerators comprising automatic means for starting and stopping operation of the refrigerator to obtain normal cycles of operation, control

means for starting and stopping said refrigerator independent of said automatic means, means for obtaining non-normal cycles of operation of said refrigerator with the temperature limits between starting and stopping being changed and common means manually operable for operating said control means and securing said non-normal cycles of operation.

10. A control mechanism for refrigerators comprising automatic means for starting and stopping operation of the refrigerator to obtain normal cycles of operation, overload protection means for normally stopping operation of said refrigerator, control means for starting and stopping said refrigerator independent of said automatic and overload protection means, means for obtaining non-normal cycles of operation of said refrigerator with the temperature limits between starting and stopping being changed and common means manually operable for resetting said overload protection means, operating said control means and securing said non-normal cycles of operation.

11. A control mechanism for refrigerators comprising means for starting and stopping operation of the refrigerator to obtain normal cycles of operation, means for securing temporary modification of the normal cycles of operation of the refrigerator with the temperature limits between stopping and starting remaining the same, overload protection means for non-normally stopping operation of said refrigerator, means for obtaining non-normal cycles of operation of the refrigerator with the temperature limits between stopping and starting being changed and common means manually operable for securing said temporary normal cycles of operation, resetting said overload protection means and securing said non-normal cycles of operation.

12. A control mechanism for refrigerators comprising means for starting and stopping operation of the refrigerator to obtain normal cycles of operation, means for securing temporary modification of the normal cycles of operation of the refrigerator with the temperature limits between stopping and starting remaining the same, control means for starting and stopping said refrigerator independent of said first means, means for obtaining non-normal cycles of operation with the temperature limits between stopping and starting being changed and common means manually operable for securing said temporary normal cycles of operation, operating said control means and securing said non-normal cycles of operation at the will of the operator.

13. A control mechanism for refrigerators comprising factory set means for starting and stopping operation of the refrigerator to obtain normal cycles of operation, means for securing temporary modification of the nor-

- mal cycles of operation of the refrigerator with the temperature limits between starting and stopping remaining the same and means for obtaining non-normal cycles of operation
- 5 of the refrigerator with the temperature limits between starting and stopping being changed, one limit being substantially the factory set low temperature and the other materially higher than the factory set high
- 10 temperature and common means manually operable for securing said temporary normal cycles of operation and said non-normal cycles of operation, both at the will of the operator.
- 15 14. A control mechanism for refrigerators comprising means for starting and stopping operation of the refrigerator to obtain normal cycles of operation, means for securing temporary modification of the normal cycles
- 20 of operation of the refrigerator with the temperature limits between stopping and starting remaining the same, means for obtaining a defrosting cycle of operation of the refrigerator with the temperature limits between
- 25 stopping and starting being changed for defrosting purposes and common means manually operable for securing said temporary normal cycles of operation and securing said defrosting cycle of operation.
- 30 15. A control mechanism for refrigerators comprising means for starting and stopping operation of the refrigerator to obtain normal cycles of operation, means for securing temporary modification of the normal cycles
- 35 of operation of the refrigerator with the temperature limits between stopping and starting remaining the same, means for obtaining a defrosting cycle of operation of the refrigerator with the stopping limit remaining sub-
- 40 stantially the same and the starting limit being materially raised for defrosting purposes and common means manually operable for securing said temporary normal cycles of operation and securing said defrosting cycle
- 45 of operation.

Des Moines, Iowa, October 24, 1932.

MALCOLM E. HENNING.
